(57) **CLAIM**

The ornamental design for a hypercube model, as shown and
described.

DESCRIPTION

FIG. 1 illustrates an elevational view of a first side of the
hypercube model.

FIG. 2 illustrates the hypercube model of FIG. 1 rotated
approximately 27.5° about a y-axis.

FIG. 3 illustrates the hypercube model of FIG. 1 rotated
approximately 45° about a y-axis.

FIG. 4 illustrates the hypercube model of FIG. 1 rotated
approximately 55° about a y-axis.

FIG. 5 is another elevational view of a second side of the
hypercube model of FIG. 1 and illustrates the hypercube
model of FIG. 1 rotated approximately 90° about a y-axis.
FIG. 6 illustrates a top plan view of the hypercube model.
FIG. 7 illustrates the hypercube model of FIG. 6 rotated
approximately 45° about an x-axis.

FIG. 8 illustrates the hypercube model of FIG. 6 rotated
approximately 55° about an x-axis.

FIG. 9 illustrates the hypercube model of FIG. 6 rotated
approximately 90° about an x-axis.

FIG. 10 illustrates the hypercube model of FIG. 6 rotated
approximately 117.5° about an x-axis; and,

FIG. 11 illustrates a bottom plan view corresponding to the
hypercube model of FIG. 6 rotated 180° about an x-axis.
